DISPENSING CONTAINER FOR VISCOUS CONDIMENTS

Morris Friedman, New York, N.Y., and Andrey V. Mackey, Ambler, Pa., assignors to Minerware, Inc., New York, N.Y., a corporation of New York, and H.M.S. Associates Co., Willow Grove, Pa., a corporation of Pennsylvania

Filed Mar. 26, 1964, Ser. No. 79,210

Term of patent 14 years

(Cl. D44—22)

FIG. 1 is a side elevational view of a dispensing container for viscous condiments showing our new design; FIG. 2 is a top view of the cover of the container of FIG. 1;

FIG. 3 is a bottom view of the container of FIG. 1; and

FIG. 4 is a fragmentary exploded side elevational view showing the cover removed from the top portion of the container of FIG. 1.

We claim:

The ornamental design for a dispensing container for viscous condiments, substantially as shown.
